(57) **CLAIM**

We claim the ornamental design for a deck recess for boat, as shown and described.

DESCRIPTION

FIG. 1 is a perspective view of a deck recess for boat showing our new design;

FIG. 2 is a front elevation view thereof;

FIG. 3 is a back elevation thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is an enlarged view of a portion of the deck recess for a boat;

FIG. 9 is a side-sectional view thereof; and,

FIG. 10 is a front-sectional view thereof, showing the deck recess for boat.

The broken lines illustrate portions of the deck recess for boat that form no part of the claimed design. The dot-dash lines illustrate the periphery of the enlarged and section cut views of the deck recess for boat that form no part of the claimed design.

1 Claim, 9 Drawing Sheets
